UNITED STATES PATENT OFFICE.

WILLIAM L. DILLMAN, OF KOKOMO, INDIANA.

CREAM-SEPARATOR.

No. 895,076.

Specification of Letters Patent.

Patented Aug. 4, 1908.

Application filed July 31, 1907. Serial No. 386,445.

To all whom it may concern:

Be it known that I, WILLIAM L. DILLMAN, a citizen of the United States, residing at Kokomo, in the county of Howard and State of Indiana, have invented certain new and useful Improvements in Cream-Separators, of which the following is a specification.

This invention relates to centrifugal cream separators, and consists essentially of an improved liner for the bowl, whereby separation of the constituents of the whole milk is effected, and a peculiar compensating bearing to take up the great vibration incidental to the operation of the bowl when rotated, and which is adjustable by a special connection between the stand of the machine and the casing of the bowl.

The invention also involves novel details of construction and for a full understanding 20 of the various novel features, reference is to be had to the following description and the accompanying drawings, in which:

Figure 1 is a vertical sectional view of a separator embodying the essential features 25 of the present invention. Fig. 2 is a sectional view on the line 2—2 of Fig. 1. Fig. 3 is a side view of the liner forming a part of the invention, partly in section. Fig. 4 is a vertical sectional view of the bearing for the 30 bowl spindle.

Corresponding and like parts are referred to in all the views of the drawings, and indicated by the same reference characters.

In carrying out the invention a machine 35 constructed in accordance therewith is comprised of the usual general arrangement of parts commonly employed for cream separators. A suitable supporting stand A is provided and projecting upwardly therefrom 40 is a vertical hollow standard 1 upon the upper portion of which is mounted a detachable head 2. The head 2 is of peculiar form and is peculiarly mounted on the standard 1. Said head comprises an approximately circular body having a cover 2^a removably mounted at one side thereof, said cover being formed with an integral arm 3 provided with a vertical bearing 4 at its inner end. A crank shaft 5 is mounted in a horizontal bearing 6 provided in the upper portion of the head 2, a suitable crank handle 7 being applied to the outer end of the shaft 5 and a large bevel gear 8 being secured to the inner

end of said shaft. The bevel gear 8 meshes with a bevel pinion 9, the latter being a part of a clutch element 10 which co-operates with a second clutch element 11 to provide a ball ratchet mechanism, the balls being indicated at 12. The pinion 9 is adapted to be actuated on operation of the shaft 5 in an obvious manner and the gearing mounted in the head 2 is designed to effect rotation of a vertical shaft 13 which is arranged within the standard 1 and the upper end of which is journaled in the bearing 4 of the arm 3 before described. The pinion 9 is loosely mounted upon the shaft 13 and the ratchet mechanism co-operating with said pinion permits of continued rotation of the shaft even though the crank handle 7 is stationary.

The head 2 is not only detachably mounted on the standard 1 but is adjustable relative thereto in order that the position of the crank handle 7 may be adjusted or varied according to the convenience of the operator. For the above purpose the upper portion of the standard 1 is received in the lower portion of the head 2 and the latter is attached to the standard by means of a set screw 14 or analogous fastening. It will be apparent that the mounting of the head 2 is such that it may be rotated and fixed in an adjusted position with readiness. Upon the lower end of the shaft 13 which extends into the base of the support or stand A is mounted a gear 15, a suitable adjustable bearing 16 being provided to receive the lower extremity of said shaft. The gear 15 meshes with a pinion 17 carried by a second gear 18 which is journaled in suitable bearings 19 clearly shown. The gear 18 engages a pinion 20 formed upon the lower end of the spindle 21 which carries the separator bowl 22, the spindle 21 being integral with the bottom of said bowl.

The bowl 22 is mounted for rotary movement in the customary manner in a peculiar bearing which will be more clearly described hereinafter. A casing 23, removably mounted upon its bottom 24, surrounds the bowl 22. The bottom 24 of the casing 23 is formed with an opening through which the spindle 21 passes, and projecting downwardly from said bottom is an annular internally threaded flange or collar 25 which is screwed upon the upper end of a neck or

tubular projection 26 extending upwardly from the base A of the stand which carries the separator mechanism. The projection 26 is formed with an internal shoulder 27 having an opening through which the spindle 21 passes and formed with a recess 28 in its upper side.

Arranged between the shoulder 27 of the projection 26 and the bottom of the bowl 23 is a compensating bearing for the spindle 21, said bearing being adjustable by relative adjustment of the bottom of the bowl casing and the projection 26, such adjustment being afforded by the threaded 10 connection between these parts. The compensating bearing above mentioned comprises a sleeve 29, snugly receiving the spindle 21 therein, and coöoperating coiled springs 30 and 31. Intermediate of its 15 ends the sleeve 29 is formed with an integral flange 32 in the upper and lower sides of which are provided circular grooves 33 in which the adjacent ends of the springs 30 and 31 are received. The lower end of the 20 spring 31 is received in the recess 28 of the shoulder 27, and the upper end of the spring 30 is received in a recess 34 formed in the bottom 24 of the casing 23 and at the periphery of the opening of said bottom. 25 The sleeve 29 is of smaller diameter than the opening in the bottom 24 of casing 23 and passes through said opening.

It will be apparent that the arrangement of the parts of the bearing just described is 30 such that the great vibration incidental to the rotation of the bowl in the actual operation of the machine is fully absorbed, and strain and jar upon the supporting means for the bowl are reduced to a minimum. 35 Furthermore the construction of the supporting parts of the compensating bearing, whereby such parts also form supporting means for the bowl is extremely advantageous in that adjustment of said parts 40 may be readily effected to correspondingly adjust the springs 30 and 31 whereby the tension of said springs may be increased or decreased as may be necessary under actual 45 conditions of service. The casing 23 surrounding the bowl 22 is made of light metal 50 and rests upon an annular shoulder formed in the outer portion of the bottom 24, being readily removable from such position.

Within the bowl 22 is arranged a peculiar 55 form of liner, the special construction of which is designed to increase the efficiency of the machine with regard to the separation of the elements of the liquid operated upon thereby. The liner is composed of a central 60 stem 35 of tubular form, the lower end of which is internally threaded to receive a threaded boss 36 which is integrally formed with the bottom of the bowl 22. The tubular stem 35 is formed with integral radially 65 curved plates or wings 36, the outer edge

portions of which substantially fit the inner side of the bowl 22. The plates or wings 36 are integrally formed at the lower portions thereof with the stem or tubular member 35, the inner edge portions of said plates being 70 spaced nearly throughout the length thereof from the members 35. In other words the plates 36 are so formed as to provide an annular space between their inner edges and the tubular stem or member 35, said space 75 comprising an upward passage for the cream as the latter is separated from the skim-milk. Between the several plates 36 of the liner are arranged at intervals, and vertically spaced from each other, a number of downwardly inclining webs 37, sets of the webs being in parallel and substantially horizontal planes and having the inner edges thereof spaced from the tubular member 35, or flush with the inner edges of the plates 36. 80

The several webs 37 comprise transverse partitions between the blades or wings 36 and said partitions are straight in cross section or from the outer to the inner edges thereof. Arranged at the upper portion of the bowl 22 is the cover therefor, said cover comprising inner and outer sections 38 and 39 respectively. The outer section consists of a body receiving the upper end of the bowl and having a gasket 40 interposed between it and the upper edge of said bowl. The inner section 38 of the cover also consists of a body portion the same being spaced at its upper side from the corresponding portion of the outer section of the cover to 95 provide a passage 41 for the skim-milk which passes through a plurality of openings 42, located near the edge portion of said inner cover section. Each of the cover sections has a tubular extension at its upper portion, the extension 38a of the inner section being spaced a portion of its length from the extension 39a of the section 39, as shown at 41, said space forming a continuation of the space or passage 41, and permitting the 100 skim-milk to pass from the passage 41 through outlet openings 43 in the outer cover section. A cream tube 44 is applied to the inner cover section 38 and conveys the cream 105 passing upwardly from the space just surrounding the stem 35, to the cream outlet 45. Mounted upon the top of the casing 23 for the bowl 22 is a milk pan 46 from which leads a spout 47. In a similar manner a cream 110 pan 47 is provided, the latter being supported upon the pan 46 and receiving the cream from the cream outlet 45. A suitable spout 48 leads off from the pan 47, and a 115 float cup 50 is supported upon acid cover, 120 in a conventional manner.

It will be understood that the stand for the separating mechanism before described will have a suitable bracket to carry the milk receptacle and may also have a cream re- 125

ceptacle just below the cream spout 48. Said stand will also be mounted upon legs preferably. However the supporting structure of the stand is immaterial within the contemplation of the invention.

The whole milk is fed to the bowl 22 through the stem or tubular member 35, the latter having lateral openings 35^a at its lower portion. The milk passes through the 10 openings 35^a and through vertical openings 37^a in the lowermost webs 37 as well as passing into the space between the member 35 and the bowl by passage around the lower edges of the lowermost webs. The spindle 15 21 of the bowl 22 is provided with an adjustable bearing at its lower end as shown in the drawings and adjustment of said spindle may be readily effected in the same manner as such adjustment may be performed in 20 regard to the shaft 13 and the gear 18.

The advantages of the several features of construction hereinbefore set forth will be obvious from the foregoing description. A ring nut 51 is screwed upon the upper extremity of the tubular member 35 of the liner and is arranged above the sections of the cover of the bowl 22. Said nut engages the tubular extensions 39^a of section 39 and prevents displacement thereof from the 25 bowl and leakage of liquid therefrom at the outer flange 52 of the cover 39.

It will be observed that the upper portion 38^a of the inner cover section has a snug sliding fit within the upper portion 39^a of the 30 outer section. The milk holes 42 are located in the section 38 and the outlet holes 43 in the outer section 39. Likewise the cream tube 44 is carried by the inner section and the upper end thereof must register with the 35 single outlet hole 45. In order, therefore, to insure proper registration of these parts I provide a slide groove upon the inner surface of the extension 39^a and into which the tube 44 is received, the tube projecting sufficiently 40 beyond the outer surface of the upper portion 38^a to effect this result, the hole 45 being at the upper end of the said groove.

It will be understood that the liner which comprises the wings 36 rotates within the 45 bowl and as a means for effecting the elevation of the separated milk within the bowl the several wings are inclined slightly from the vertical, the major portion of the milk being elevated by the wings by reason of such inclination somewhat in the manner of a spiral conveyer.

Having thus described my invention what I claim as new and desire to secure by Letters Patent of the United States, is:

60 1. In a cream separator, the combination of a stand, a separator bowl mounted thereon, a spindle supporting said bowl, means for rotating the spindle and bowl at high speed, a casing for the bowl, a compensating bearing 65 receiving the spindle aforesaid, and means

connecting the casing with the stand and operable to effect adjustment of the compensating bearing.

2. In a cream separator, the combination of a stand, a separator bowl mounted thereon, a spindle supporting said bowl, means for rotating the spindle and bowl at high speed, a casing for the bowl, a compensating bearing receiving the spindle aforesaid, and means for adjusting the relative positions of the 75 casing and the stand and simultaneously adjusting the parts of the bearing aforesaid.

3. In a cream separator, the combination of a stand, a separator bowl mounted thereon, a spindle supporting said bowl, means for rotating the spindle and bowl at high speed, a casing for the bowl, a compensating bearing for the spindle and the bowl, and comprising spring elements, and an adjustable connection between the casing and the 85 stand for effecting adjustment of the tension of the spring elements of said bearing.

4. In a cream separator, the combination of a stand, a separator bowl mounted thereon, a spindle supporting said bowl, means for 90 rotating the spindle and bowl at high speed, a casing for the bowl, a bearing receiving the spindle of the bowl and comprising compensating springs and a sleeve, and a threaded connection between the casing and the stand 95 permitting of adjustment of these parts and simultaneous adjustment of the tension of the compensating springs.

5. In a cream separator, the combination of a supporting stand, separator mechanism 100 mounted thereon, and including a separator bowl, operating mechanism for rotating said bowl, a casing surrounding the bowl and having a detachable bottom, the stand being formed with an outward projection adjustably connected with the bottom of the casing and having an annular shoulder thereon, a spindle supporting the bowl and passing through the bottom of the casing aforesaid, a compensating bearing for said spindle comprising a sleeve receiving the same and having an annular flange, springs surrounding said sleeve and having adjacent ends bearing against its flange, the remote ends of the springs bearing against the bottom of the 110 casing of the bowl and the annular shoulder of the projection of the stand, relative adjustment of the bottom of the casing and the projection connected therewith being adapted to effect adjustment of the tension of the 115 springs of the compensating bearing.

6. In a cream separator, the combination of a bowl, having a threaded boss projecting upwardly from its bottom, a liner arranged in said bowl and comprising a tubular member having a plurality of radially curved plates longitudinal thereof, the lower portions of said plates being integral with the tubular member and the upper portions being spaced at the inner edges from said mem- 120 125 130

ber, downwardly inclined transverse webs connecting the radially curved plates at intervals in the length thereof, a cover for the bowl composed of inner and outer sections 5 each comprising a body having a tubular extension at its upper portion, the body of the inner section and a portion of its extension being spaced from the outer section to form a passage for skim-milk, the lower portion of 10 the inner section being provided with suitable openings leading to the aforesaid passage, a cream tube applied to the inner sec-

tion, the outer section having a cream outlet extending from the upper end of said cream tube, and a ring nut applied to the upper end of the tubular member of the liner and preventing displacement of the sections of the bowl:

In testimony whereof I affix my signature in presence of two witnesses.

WILLIAM L. DILLMAN.
